[57] CLAIM

The ornamental design for a cotton swab, as shown and described.

DESCRIPTION

FIG. 1 is a front elevational view of a cotton swab, showing my new design;

FIG. 2 is a right side elevational view of FIG. 1;

FIG. 3 is a front elevational view of a second embodiment of the cotton swab;

FIG. 4 is a right side elevational view of FIG. 3;

FIG. 5 is a front elevational view of a third embodiment of the cotton swab;

FIG. 6 is a right side elevational view of FIG. 5;

FIG. 7 is a front elevational view of a fourth embodiment of the cotton swab;

FIG. 8 is a right side elevational view of FIG. 7;

FIG. 9 is a front elevational view of a fifth embodiment of the cotton swab; and

FIG. 10 is a right side elevational view of FIG. 9.

For each of the front plan views described above and shown in the accompanying drawings, the corresponding top, rear and bottom plan views are identical. For each of the right side views described above and shown in the accompanying drawings, the opposing left side views are identical.
